PLOW SWEEP

Colbert Resser Smith, Fairmont, N. C., assignor
to Cohen Purvis Leggett, Robeson County,
N. C.

Application November 15, 1935, Serial No. 50,026

2 Claims. (Cl. 97—205)

This invention relates to a plow sweep or the like.

It is particularly aimed to provide an article of this character, having wings which are readily 5 adjustable so as to occupy different extended as well as normal positions.

It is especially aimed to provide such a construction wherein connection at all times and at all 10 adjustments between the wings and the remainder of the sweep is rigid, and consists of inter-engaging ribs and slots and bolts or the like.

The more specific objects and advantages will become apparent from a consideration of the description following taken in connection with accompanying drawing illustrating an operative embodiment.

In said drawing:—

Figure 1 is a plan view of the sweep;

Figure 2 is a bottom or inverted plan view of 20 the sweep;

Figure 3 is a longitudinal sectional view taken on the line 3—3 of Figure 1;

Figure 4 is a cross sectional view taken on the line 4—4 of Figure 1; and

Figure 5 is a cross sectional view taken on the line 5—5 of Figure 1.

Referring specifically to the drawing, 10 designates a plow sweep or the like generally of conventional configuration, being pointed, as shown, 30 and curved longitudinally and transversely, as desired. Such sweep is made in a single piece and has integral wings 11 at each side thereof, extending rearwardly. A central stub 12 on said sweep has a central longitudinally extending slot 35 13 to accommodate means to fasten the same to a beam or the like. The rear end edges of the wings 11 are preferably beveled or chamfered, as shown, at 14.

Disposed against the under surfaces of the 40 wings 11 are extensions or adjustable wings 15, whose rear or free ends conform generally in shape to the free or rear ends of the fixed wings

11. Such adjustable wings 15 have central longitudinal slots 16 therethrough, which snugly and slidably engage depending longitudinal ribs 17 integral with the fixed wings 11. As a result of this construction, the extensions or adjustable 5 wings 15 are slideable relatively to the wings 11, and may be arranged at any desired adjustment or extended position with respect to the wings 11. Removable bolts rigidly secure the wings 15 to the wings 11 and comprise a shank 18 extending 10 through openings 19 in the wings 11 and through the slots 16. Such shanks 18 have countersunk heads 20 engaging enlargements of the openings 19, and also have nuts 21 threaded thereon and abutting the under surface of the wings 15. 15

Various changes may be resorted to provided they fall within the spirit and scope of the invention.

I claim as my invention:—

1. A sweep of the class described, having wings, 20 extension wings engaging the under surface of the first-mentioned wings, means to secure the last-mentioned wings in adjusted position with respect to the first-mentioned wings, comprising ribs on one set of wings, the other set of wings 25 having openings in which said ribs are disposed, and fastenings passing through the wings of the different sets.

2. A sweep of the class described, having wings, extension wings engaging the under surface of 30 the first-mentioned wings, means to secure the last-mentioned wings in adjusted position with respect to the first-mentioned wings, the first-mentioned wings having central longitudinal ribs 35 on the under surface thereof, the remaining wings having longitudinally extending slots open at one end and engaging said ribs, bolts passing through the wings at said slots operable to secure the wings together, and the rear ends of the first- 40 mentioned wings being beveled.

C. RESSER SMITH.
